[57] CLAIM

The ornamental design for a head band, as shown and described.

DESCRIPTION

FIG. 1 is a perspective view of the head band showing my new design;

FIG. 2 is a front view of the head band shown in FIG. 1 in its extended position;

FIG. 3 is a rear elevational view thereof;

FIG. 4 is a top plan view thereof, the bottom is essentially the same;

FIG. 5 is a perspective view of the head band with its cloth cover extended in a first position; and,

FIG. 6 is a perspective view of the head band with its cloth cover extended in a second position.

The broken line showing of the human form in FIGS. 1, 2, and 3 is for illustrative purposes only and forms no part of the claimed design.
